SELECTOR FOR SORTING MACHINES

Ernest Rose, Washington, D. C., assignor to International Business Machines Corporation, New York, N. Y., a corporation of New York

Application February 9, 1935, Serial No. 5,804

3 Claims. (Cl. 209—110)

This invention relates to a selector for sorting machines, particularly of the well known Hollerith type, whereby documents of a particular classification or several specific classifications may be sorted.

It is an object of the invention to provide a selecting mechanism which may be quickly and easily set for desired classifications and maintained in such set position until the sorting has been accomplished for such desired classifications when the selecting mechanism may be quickly and easily restored to its original position.

It is a further object of the invention to provide a restoring device which will release a plurality of selector keys at one time thereby eliminating the necessity of restoring individual selector keys one at a time.

A further object is to provide a visual distinction between selector keys which have been set and those unset whereby the operator may easily recognize the selecting classifications for which the selector has been set.

The invention is designed to provide a selecting arrangement which can be used with a sorting machine with a minimum of alterations therein.

Various other objects and advantages of the present invention will become apparent from the detailed description below and will be particularly pointed out in the following description and claims and shown in the preferred embodiment of the invention illustrated in the drawings, in which

Figure 1 is a diagrammatic view of a sorting machine and shows the card feeding and conveying mechanism, the card guiding devices and the analyzing device,

Figure 2 is a vertical elevation of the brush holder and special analyzing brush shown in Figure 1 and viewed from the left in the latter figure,

Figure 3 is a detail view in elevation showing the driving connections between the selector device and the sorting machine,

Figure 4 is a perspective view of a battery of stationary commutators to cooperate with the selector keys with certain details omitted for clarity and illustrating the manner in which said commutators may be assembled,

Figure 5 is a side view of the stationary commutator controlling the shunting of the sorting magnet,

Figure 6 is a side view of a stationary commutator which cooperates with the selector keys for a column,

Figure 7 is a partial cross sectional view through

the battery of stationary commutators along section line 7—7 of Figure 6 looking in direction of arrows,

Figure 8 is a plan view of the selector key board, Figure 9 is a partial perspective view of the key board,

Figure 10 is a longitudinal cross sectional view through one of the units of the key board with parts in elevation,

Figure 11 is a partial enlarged view of a portion of Figure 10 showing a key in set position,

Figure 12 is a cross sectional view along the section line 12—12 of Figure 11 looking in the direction of the arrows,

Figure 13 is a cross sectional view partially through the key board and taken at right angles to the view in Figure 10, and

Figure 14 is a circuit diagram with certain of the commutator-key board circuits omitted for greater clarity showing the manner in which the invention is connected to the sorting machine.

The present invention has been shown as applied to a sorting machine of a type now well known in the art. The construction and operation of the card selecting, conveying and guiding mechanism and the general arrangement of the circuits are fully shown and described in Letters Patent No. 1,741,985, granted December 31st, 1929 to E. A. Ford, while the mechanism for feeding cards from the magazine and the brush holder for the analyzing brush are shown and described in Letters Patent No. 1,741,992, granted December 31st, 1929 to Harry Kleckler.

The foregoing mechanisms will be only briefly explained herein since said patents contain a full description of well known mechanisms of which the present invention is an improvement.

The motor 10 which drives the sorting mechanism is started by depressing a starting key 11 which establishes a circuit from source 12, line 13, motor relays 14, card relay 15, starting key 11, now closed, stop key 16, to the line 17 and back to source 12. Energization of relays 14 closes contacts 14a thereby starting the motor 10 while energization of relay 15 closes contacts 15a and connects the card lever contacts 18 in parallel with the starting key 11. The starting key 11 is held depressed until cards begin to pass the analyzing brushes after which the card lever contacts 18 close thereby establishing a holding circuit for the relays 14 and 15. The starting key 11 may be released after the contacts 18 have established the holding circuit. When the last card has been fed from the card magazine and has passed the analyzing brush the card lever 55

contacts 18 open thereby breaking the holding circuit for relays 14 and 15 and the motor stops. The motor may also be stopped at any time by depressing the stop key 16 which opens the holding circuit in a similar manner.

- The motor 10 is connected by suitable driving connections such as a belt or gearing to a main drive shaft 19 (Fig. 1) and drives the feeding rollers 20 by means of suitable gears 21 and 22.
- 10 The cards 23 are fed from the magazine by means of a picker 24 carried by a reciprocating frame 25 sliding in suitable guides and operated by eccentric pins 26 carried by a cross shaft (not shown) driven by the shaft 19. A link 27 connects each pin 26 to a rock arm 28 journaled upon a cross shaft 20, each of the arms 28 having a slot at its upper end which engages a pivoted member carried by the frame 25. It will be clear therefore, that rotation of shaft 19 will cause the frame 25 to reciprocate from right to left (Fig. 1) to feed a card 23 from the magazine. The timing of the parts is such that a card 23 is fed from the magazine once during each revolution of the feed rollers 20.
- 15 Extending crosswise of the machine above and parallel with the shafts supporting the card feeding rollers 20 is a bar 30 adapted to support and guide a carriage 31 carrying a detachable brush holder 32. The carriage 31 is adapted to be shifted manually and crosswise of the machine or front and rear, as viewed in Fig. 1, and carries a post 33 which cooperates with a hole 34 in the brush holder 32 to hold the latter in place. The brush holder 32 is locked in place by means of a rotatable pin 35 having a notch 36 near its midpoint of about the same radius as the pin 33 while the latter has a similar notch 37 near its end of a radius about equal to the radius of the pin 35. When both notches 36, 37 are facing each other the brush holder 32 may be easily removed but if a handle 38 carried by pin 35 is turned about 90° the notch 36 in pin 35 is rotated to the position shown in Fig. 1 and the solid part of the pin 35 will be brought into the notch 37 in pin 33 and thereby prevents removal of the brush holder 32.
- 20 Ordinary sorting operations of the sorting machine require a single brush which may be of the form disclosed in Patent 1,741,992 in which the brush holder is composed of two parts which are insulated from each other, the lower part being of metal permanently fastened to the upper part and carries a card analyzing brush and a contact shoe. The contact shoe bears upon a contact rail 39 carried by the bar 30 and insulated therefrom so that the brush may be set to analyze any desired column of the card and still remain connected to the control circuits of the machine.
- 25 When it is desired to carry out the special sorting operation whereby several classifications may be sorted, the ordinary brush holder is removed and replaced by a special brush holder having six brushes adapted to analyze simultaneously six adjacent columns of the record card.
- 30 The special brush holder is illustrated in Figs. 1 and 2 in which it is shown as comprising a substantially U-shaped frame 32, between the downwardly extending arms 40 of which are supported six brush retainers 41 insulated from each other and from the frame 32. The brush retainers 41 carry the brushes 42 which are held in place by set screws 43 the lower ends of the retainers being slotted as at 44, to permit the

upon the card as it passes over the rotatable and insulated contact roll 45.

The brush retainers 41 are supported by pins 46 which pass through the arms 40 of holder 32 and are held in said arms by means of pins 47 which pass through the arms 40 and the pins 46, suitable insulating bushings surrounding the pins 46 and preventing the metal of the brush retainers from touching the pins 46. The retainers 41 are insulated from each other and from the arms 40 by means of flat separators 48 of insulating material and each is provided with a connector lug 49 to which are soldered or welded the individual wires 50 connecting the brushes 42 to the selector circuits. Interposed between the extreme right and left separators 48 (Fig. 2) and the arms 40 are plates 51 co-operating with set screws 52 carried by the arms 40. It will be clear that the set screws 52 may be turned in either direction to adjust the brushes slightly in a direction axial with respect to the set screws 52 and, when said brushes have been once set properly, said screws 52 may be both tightened to hold the brush retainers firmly in place. The individual wires 50 may be cabled and of a sufficient length to permit setting the carriage 31 to position the brushes in coincidence with any six columns of the record card as it passes over the contact roll.

Before proceeding with a detailed description of the special selector mechanism a brief description will be given of the operation of the sorting machine when operated in the ordinary manner. The single brush used for normal sorting operations is indicated by broken lines (Fig. 14) and bears the reference numeral 53. It will be understood that the special brush holder 32 has been replaced by the ordinary brush holder having a single brush and that the special selector circuits, hereinafter to be more fully described, have been disconnected by means of certain switches provided for that purpose. The brush 53 is positioned to analyze the desired column on the record card as the card is fed from the first set of feed rollers 20 (the right set, Fig. 1). The guide blades 54 rest upon the top of an armature 55 which is controlled by a sorting magnet 56, the armature lying level with and between two fixed guide plates (not shown) over which the card is adapted to slide under the influence of the feed rollers 20. The ends of the guide blades 54 are so spaced relative to the analyzing brush that the brush will sense an index-point perforation at the instant the left edge of the card underlies the end of the guide blade 54 corresponding to that index point position. Each guide blade leads to a sorting pocket (not shown) which is designed to accumulate all of the record cards having a given index-point perforation in the column analyzed.

There are thirteen such sorting pockets, the thirteenth pocket being for the reception of unperforated cards and commonly called the "reject" or "R" pocket. The other twelve pockets correspond to the twelve index-point positions of the record card and each has a guide blade 54 leading thereto. The first blade on the right (Fig. 1) corresponds to the "9" pocket, the next corresponds to the "8" pocket, and the others in order, from right to left, correspond to the "7", "6", "5", "4", "3", "2", "1", "0", "11", and "12" 70 pockets, respectively.

As the card passes beneath the brush 53, the left edge passes beneath each blade end and, if a perforation should be present in any of the index point positions named, said perforation will be 75

sensed by the brush 53 at the same instant the left edge of the card underlies the end of the particular blade 54 corresponding to the sorting pocket adapted to accumulate cards perforated at that particular index-point.

When the perforation is sensed by the brush 53 contact will be made with the contact roll 45 and a circuit established as follows: Source 12, line 13, sorting magnet 56, brush relay 57, line 58, 10 contact rail 39, brush 53, contact roll 45, contact roll brush 59, commutator brush 60, through the commutator segment corresponding to the index-point perforation sensed, common brush 61, line 17, back to source 12. Energization of the brush relay 57 closes contacts 57a and establishes a holding circuit for the relay 57 through a commutator segment 62, brush 63 and the common brush 61 to the source 12. The segment 62 is of sufficient circumferential length to hold the circuit until the last index-point position has passed beneath the brush after which event occurs the brush 63 passes out of contact with said segment 62 thereby breaking the holding circuit for relay 57. The energization of the sorting magnet 56 causes the armature 55 to drop thereby lowering all of the blade ends 54 not resting upon the record card analyzed and, as a consequence thereof, a gap is made between the last blade on the left (Fig. 1) which is held up by the card 30 and the next adjacent lowered blade into which the card is carried by the feeding rollers 20. The card will thereafter be guided to the appropriate sorting pocket by means of suitable feeding rollers similar to the rollers 20.

35 Patent No. 1,741,985 gives a more detailed description of the construction and operation of the commutator 64 cooperating with the brushes 60, 61 and a reference to that patent will fully explain its purpose. Since the present invention 40 does not directly involve the said commutator, it will not be described in detail herein. It will be understood that each bar or spot 65 on the commutator has been made current conducting in each index point position as explained in detail 45 in said patent.

The special selector device is arranged to be attached to an existing sorting machine without any structural alteration in the machine and for that reason may be made a compact and self-contained unit or may be preferably divided into two units as shown in Fig. 1 in dotted lines at 66 and 66A. The casing 66 containing the battery of stationary commutators hereinafter described may be attached to the rear of the machine and 50 near the right end of the machine and is shown particularly in Figs. 4, 5, 6, and 7. The casing 66A containing the keyboard and preferably flexibly electrically connected with the casing 66 is preferably positioned at the front of the sorting machine so as to permit easy access thereto.

Journalled within the casing 66 is a shaft 67 which extends forwardly and exteriorly of the casing (to the left Fig. 3) and carries mounted thereon a gear 68 meshing with the gear 22 carried by shaft 19 and driving the lower right feeding roller 20 (Fig. 1). The gear 68 has a hub which extends through an outboard bearing 69 carried by a bracket 70 attached to the left side of the casing 66.

70 The shaft 67 has mounted thereon a series of brush holders 71, six in number, and a brush holder 72 cooperating with the commutator block 73 which shunts the sorting magnet 56. The brush holders 71 and 72 are insulated from

the shaft 67 in any desired manner such as by the insulating rings 74.

Located within the casing 66 are preferably four supporting rods 75 for the commutator blocks 76 and the above mentioned block 73. The 5 blocks 76 and the block 73 are made of insulating material such as bakelite or the like and are spaced from one another by the spacers 77 carried by the rods 75 thereby providing spaces through which the leads to the contacts 78 upon 10 the blocks 76 and to the contact 79 upon the block 73 may be led.

As mentioned above, the brush holders 71 and the brush holder 72 are insulated from the shaft 67 by the rings 74. These insulating rings are 15 fixedly secured to the shaft 67 in any desired manner and the brush holders 71 and 72 are in turn fixedly secured to the insulating rings 74 by means of the set screws 80. This permits any circumferential and axial adjustment desired for 20 the brush holders upon shaft 67. The brush holders are made of conducting material such as copper or the like and are provided with an annular groove 81 against which bears a flexible lead 82 secured to a side of the blocks 76 and 73 25 as for example by the screws 83.

Secured adjustably in the holders 71 by means of the set screws 84 are the brushes 71' and secured in holder 72 in like manner is brush 72'.

The stationary commutators have the contacts 78 therein which constitute the commutator bars and are insulated from each other. There are twelve commutator bars numbered as shown in Fig. 6 from 0 to 9 and 11 and 12. As above mentioned, six commutator blocks 76 are provided although a greater or less number may be provided depending upon the special type of work or rather cards which are to be sorted.

The brush 71' contacts the fixed commutator bars in succession and each brush 71' is connected in series with the brushes 42 previously described. In the embodiment of the invention shown there are six brushes 42, but in Fig. 14 the connections to the first commutator only are shown although the remaining brushes and commutators are similarly connected.

It is to be noted that each circumferential row of commutator bars in each block 76 corresponds to a column on the record card to be analyzed and each bar 78 corresponds to an index-point 50 position in such column with which it is adapted to cooperate. The rotation of the brushes 71' are so timed that the bars corresponding to a given index-point position are in contact with brushes 71' at the instant the brushes 42 are 55 reading the same index-point positions on the card.

The commutator block 73 cooperating with the brush 72' is adapted to shunt the sorting magnet 56 during special sorting operations. In order 60 to permit normal sorting operations there is provided a switch 111 which may be opened to prevent shunting of the sorting magnet. This switch may be mounted in the casing 66 or exterior thereto and may be of any desired type. The 65 block 73 as above mentioned, is provided with a single contact 79 which extends along the greater part of the periphery of the cut-out portion of the block and cooperates with the brush 72' in a manner and for a purpose explained more 70 in detail hereinafter.

The construction of the key board disposed in the casing 66A will now be described. In the particular embodiment of the invention shown only six units A, B, C, D, E and F are disclosed 75

although, as is obvious, the number may be increased or diminished as desired in accordance with the number of columns upon a card it is desired to analyze at one time. Since the units 5 are all alike only one will be described.

Each unit is designed to contain all the contact keys for a single column upon the card being analyzed. The contact or selector keys are indicated generally at 85 and are disposed within 10 a casing 86 having a cover 87 of bakelite or other insulating material. The cover 87 is preferably detachably secured to the casing 86 by screws 88 or any other desired means and is preferably of sufficient thickness so as to serve as the sole 15 guide for the stems 89 of the keys 85.

The stems 89 are of a cross section so as to prevent rotation thereof and in the present instance, are shown as square in cross section and accordingly the cover 87 is provided with square 20 guiding apertures 90 for the stems 89.

The keys 85 comprise the key heads 91 carrying indicia thereon corresponding to the indicia upon a column of a card and the stems 89. Encircling the stems 89 and disposed between the heads 91 25 and the upper surface of the cover plate 87 are coil springs 92 constantly urging the keys to their uppermost position whereby the contact ring 93 of brass or any conducting material loosely mounted upon each stem by means of 30 rivet 94 is brought into contact with spaced contacts 95.

The contacts 95 are preferably flexible spring contacts of the form shown so as to make a wiping contact with ring 93 and are secured to the 35 under surface of cover plate 87 by screws 96 or any desired means.

The ring 93, as stated, is loosely mounted upon stem 89 and this is accomplished by making the aperture 97 therein slightly larger than the cross 40 section of the stem so that the ring may pivot to some extent upon the stem and thereby ensure making contact with both contacts 95 if one of the contacts should extend further from the cover 87 than the other.

The stem 89 is cut away at the lower end 45 thereof to accommodate pawl 98 which is pivoted by pivot 99 to the extreme lower end of stem 89 and the pawl 98 is urged by flat spring 100 constantly away from stem 89. A shoulder 101 upon 50 stem 89 extends into the path of pawl 98 and limits its movement away from stem 89.

In each unit there is provided a plate 102 slidingly mounted in the U-shaped guides 103 secured to the side walls of the casing 86 by 55 screws 104 and the plate is provided with rectangular openings 105 accommodating stems 89 and somewhat larger than the cross section of stems 89 as shown particularly in Fig. 12. In place of guide 103 it is obvious that a pair of angle irons 60 may be used.

At one end the plate 102 terminates in a rod shaped portion 106 which extends through aligned apertures 107 and 108 in casings 86 and 65 66A respectively. The portion 106 ends in a threaded portion to which is screwed a knob 109 serving as a handle. Encircling the rod shaped portion 106 and positioned between the wall of the casing 86 and shoulders 110 upon plate 102 is a coil spring 115 as shown particularly in Figs. 70 11 and 12.

At the other end of the unit from handle 109 there are aligned openings 116 and 117 in casings 86 and 66A through which the circuits to the contacts 95 may be led.

75 The operation of the keys takes place as fol-

lows. When a key is depressed against the action of spring 92 the ring 93 is moved away from the contacts 95 as shown at the right in Fig. 13 and at the same time the pawl 98 is brought below the lower surface of plate 102. The spring 100 then 5 comes into action and urges pawl 98 outwardly as shown in Fig. 11 and then when pressure is relieved from the key, the key is maintained in depressed position by the pawl 98 contacting the lower surface of plate 102 and thereby maintains 10 ring 93 out of contact with contacts 95. A plurality of keys in a single unit may be locked in depressed position in the same manner.

After the cards have been analyzed and a new setting is desired, then in such case it is merely 15 necessary to pull the handle 109 against the action of spring 115 whereby the apertures 105 in the plate 102 will be brought forwardly so that the pawls 98 even when in outward position will pass therethrough under the action of spring 92 20 and thereby restore the keys 85 to their original position so that the selector may be reset.

In the embodiment shown it is necessary to release the keys 85 in each unit independently 25 of the others, but as is obvious, all of the portions 106 may be fixedly connected together exteriorly 30 of the casing 66A so that all of the plates 102 in the key board may be operated as a unit and thereby release all the keys which have been set throughout the key board with one motion. 35

This same result may be accomplished by providing a detachable connection between the slides 102. This may consist of a plate member having spaced slots therein which may be slipped over the portions 106 between knobs 109 and 35 casing 66A. A pull upon such plate member 40 would have the effect of clearing all set keys.

The selector device depends for its operation upon the fact that an unperforated card passing the analyzing brush will not affect the sorting 40 magnet. Not having a perforation in any index point position, the unperforated card will pass beneath the blade ends 54 of all of the guide blades leading to sorting pockets and will be guided eventually into the "R" or "reject" pocket 45 which usually is the first pocket to the left of the analyzing brush as viewed in Fig. 1. It will be perceived that if it is desired to separate certain specified cards from the others it is merely necessary to nullify the presence of the identifying 50 perforations in the cards to be selected in order to permit said cards to be conveyed to the "R" pocket while the operation of the sorting magnet for the undesired cards will not be interfered with. In other words, the present invention 55 contemplates selection by rejecting the desired cards and diversion of the undesired cards so that the former will be guided to the "R" pocket and the latter to some other pocket such as, in the present case, the "12" pocket. 60

The selector device is so arranged that the effect of each of the perforations representing the identifying number in the desired cards are neutralized by depressing the corresponding key in the key board so that an open circuit will occur 65 when each of said perforations is sensed by an analyzing brush 42 while the perforations in undesired cards will affect the brush relay so as to set up a circuit which eventually will be effective to control the sorting magnet at the "12" 70 position to divert the undesired card to the "12" pocket.

In order to accomplish the foregoing result the keys are set so that no circuit can be established therethrough in any of the index-point positions 75

representing the cards to be selected while the sorting magnet is shunted except at the "12" position and during the gap between successive cards. For this reason the gap 124 between the 5 ends of the contact 79, see Fig. 5, is of a length to permit the establishment of the shunt circuit for the sorting magnet from the "9" to the "11" position, the shunt being removed at the "12" position of one card and reestablished slightly 10 before the "9" position of the card immediately following.

For the purpose of preventing excessive sparking at the brush 72' when the circuit is broken at the "12" position, there is provided a condenser 113 connected in parallel with the sorting magnet and contained within the casing 66 and a glass insert 114 which is set flush with the contact 79 where the brush 72' breaks the circuit through contact 79. The glass insert prevents the 20 spark created by the break in the circuit from burning the insulating material of which block 73 is constructed.

The circuits from the brushes 142 to the sorting connection 39 through the stationary commutators and keyboard are as follows, reference being had to Fig. 14. In this figure the circuits from the brush 42 at the "1" position is only shown but the other circuits are similar and have not been shown for greater clarity.

30 The individual wires 50 from the brushes 42 have connected thereto in series switches 130. A lead 125 goes from switch 130 at the "1" position to brush 71' of the first commutator. In Fig. 14 only the unit of the keyboard corresponding to 35 the first commutator is indicated.

From commutator bar 78 at the "12" position a lead 131 goes to one of the contacts 95 at the "12" position key; then by way of ring 93 to the other contact 95; then by lead 132 to common lead 40 133 to the sorting connection 39.

From the commutator bar 78 at the "11" position, lead 134 goes to contacts 95 at the "11" position key and thence by wire 135 to common lead 133. In the same manner, lead 136 goes from "0" 45 bar to "0" key and by 137 to 133. From "1" bar lead 138 goes to "1" key and is connected by 139 to 133. From "2" bar lead 140 goes to 133. From "3" bar, lead 142 to "3" key and then lead 143 to 133. Similarly from "4", "5", "6", "7", "8", and 50 "9" bars there are leads 144, 146, 148, 150, 152 and 154 to the corresponding keys and from the corresponding keys to the common lead 133 are leads 145, 147, 149, 151, 153 and 155 respectively.

It will be assumed that it is desired to select 55 from a given batch of cards all cards having perforations representing the number 458346 in the field assigned to the identifying number. The switch 111 is closed and also the six switches 130 are closed. The ordinary brush holder carrying 60 the brush 53 is removed and the special brush holder 32 put in its place and then the carriage 31 is shifted in a well known manner to bring the six brushes 42 into position to sweep the six columns on the record card corresponding to the 65 field assigned to the identifying number. If the identifying number had only four digits then two of the switches 130 would be left open.

The selector keys 85 in the various units A, B, C, D, E, and F are then set so that all except 70 those representing the digits of the identifying number are current conducting with their rings 93 in contact with contacts 95. This is quickly and easily accomplished by merely depressing the keys in the various units corresponding to 75 the identifying number. With the identifying

number above given, in A unit key "4" is depressed; in B unit, key "5"; in C unit, key "3"; in D unit, key "3"; in E unit, key "4" and in F unit, key "6". The depressed keys will break the current between their associated contacts 95 5 since their associated contact rings 93 will be held removed from contacts 95 by the pawls 98 engaging the under surface of plates 102.

It is apparent that a flow of current cannot be established through the commutator bars 78 10 representing the desired number when the brushes 42 encounter the perforations representing that number and any card having the desired number will not affect the circuits in any way since the only way in which the brush relay 15 57 can be energized is jointly through a perforation in the card analyzed, a brush 42, a bar 78 and a key 85 in non-depressed condition. However, the keys 85 in the index-point positions involving the desired number are depressed and 20 therefore the desired cards will pass beneath all of the blade ends 54 and be conveyed to the "R" or reject box.

When a card is analyzed having a perforation in one or more other index point positions, that 25 is, having perforations representing a number other than the number 458346, a circuit will be established as follows: source 12, line 13, contact 79 (see Fig. 5), brush 72', switch 111, previously closed, brush relay 57, thereby closing contacts 30 57a, line 58, sorting connection 39, line 133, then through a non-depressed key 85, commutator bar 78, brush 71', line 125, a switch 130, previously closed, line 50, brush 42, contact roll 45, contact roll brush 59, line 160, brush 60, commutator 64, 35 common brush 61 and line 17 back to source 12.

The closing of contacts 57a by relay 57 sets up a holding circuit for the relay through brush 63, segment 62, common brush 61 and line 17, to the source 12. However, the sorting magnet 40 56 is shunted by contact 79 of block 73 so that for the time being, nothing else happens. When the card under the brushes 42 reaches the "12" position the gap 124 breaks the shunt circuit and transfers the holding circuit of relay 57 to the 45 sorting magnet 56 thereby energizing said magnet and causing the card to go to the "12" pocket.

It may happen that none of the perforations in a card analyzed by the brushes 42 correspond to the perforations representing the identifying 50 number of the desired cards. When such is the case, the first perforation encountered by one of the brushes 42 will set up the relay 57 and the perforations subsequently encountered will have no effect although the keys 85 are in current 55 conducting position.

This invention has been so devised as to form a compact and self-contained device which may be readily mounted upon an existing sorting machine without requiring any changes other than 60 a slight reconnection and rearrangement of the circuits and the attachment of suitable supporting brackets to the frame of the machine. It may be readily connected and disconnected at the will of the operator and imposes no appreciable additional load on the driving motor.

The present invention is not limited to selecting 65 cards according to a single identifying number, but is capable of selecting all the cards of a complete series, for instance, all cards bearing identifying numbers ranging from 458341 to 458349 inclusive. This is obtained by merely depressing keys 85 in the sixth unit or unit F at positions "1", "2", "3", "4", "5", "6", "7", "8", and "9".

When the batch of cards is passed through the 75

machine no circuit can be set up by the presence of perforations representing the number "4" in the first column, the number "5" in the second, the number "8" in the third, the number "3" in the fourth, the number "4" in the fifth or the numbers 5 "1" to "9" inclusive in the sixth column or units place, since the keys 85 will be non-current conducting for all positions except "0", "11" and "12" 10 positions and consequently all cards of the desired series will be rejected and all others will be conveyed to the "12" pocket.

The present invention may be used to select record cards having identifying numbers up to 15 six digits. However, it is not limited in scope to numbers of six digits as, by providing additional 20 brushes 42, additional commutators 16 and additional units for the key board, the device may be used to select numbers having any desired number of digits. The device may be provided with as 25 many analyzing brushes as there are columns on the record card, each brush having its corresponding commutator and keyboard unit. Under ordinary conditions numbers will seldom have more than six digits so that six brushes and associated mechanisms are more than ample for most purposes.

Nor is the invention limited to use in connection with a sorting machine alone, since it may be built in the form of an attachment to a tabulating 30 machine to select the card to be operated upon by said machine. This may be readily accomplished by delivering the desired cards directly to either the card magazine or the feeding rollers of the tabulating machine instead of accumulating the 35 cards in the "reject" sorting pocket.

As is obvious from the above, the actual setting of the selector for a desired number or series of numbers is simplicity itself and can be accomplished in a minimum of time. The clearing of the 40 selector can also be accomplished in a minimum of time and if desired by a single motion. This permits the operator to greatly increase the number of classifications which may be run in a given time.

I claim:—

45 1. In a sorting machine, sorting mechanism including a single magnet for selectively controlling the sorting mechanism, a series of record sensing brushes each sensing the index-point positions of one of the columns of a field in which record 50 identifying designations representing serial numbers or the like are placed; a series of sorting control circuits connecting said brushes to said magnet, each sorting control circuit being connected to a single brush and consisting of a selecting 55 commutator having a series of fixed commutator segments valued according to the respective index-point positions of the column sensed by the particular brush to which the sorting control circuit

is connected, and a series of switches, one switch for each bar, for connecting the bars of each series directly to the sorting magnet; and a keyboard comprising a plurality of banks of manually 5 depressible keys, each bank being associated with the series of switches of one sorting control circuit and operating said switches to open same whereby the sorting magnet is controlled in accordance with numbers and the like set up on said keyboard.

2. A multi-column selector attachment for sorting machines in which the sorting mechanism is selectively controlled by a single sorting magnet; a series of multi-column selector circuits, 15 each circuit consisting of a record sensing brush, a rotary contact member connected directly to said brush, a series of fixed commutator bars over which said contact member wipes in succession, each bar corresponding to an index-point position of a column in a serial number field in the 20 records sensed by a corresponding sensing brush and a series of pairs of switches, each pair of switch contacts normally connecting one of the bars of each series to said sorting magnet; and a keyboard comprising a series of banks of 25 manually depressible numeral keys, each bank being associated with a series of commutator bars and its related series of switches whereby the depression of any selected key in any bank will open the associated switch contacts and thereby disconnect the sorting magnet from the commutator bar associated with said switch.

3. A multi-column selector attachment for record controlled machines comprising a single machine operation controlling magnet, a group of 35 record sensing brushes for sensing designations in the columns of a record field devoted to recording serial numbers the digits of which said designations represent, a series of selecting circuits for conducting current from each brush to the magnet, each selecting circuit causing the magnet to be controlled in accordance with a single digit represented by a designation sensed by the brush to which it is connected, each circuit having a series of fixed contacts, a rotary wiper moving 40 over said contacts seriatim to connect the brush with said magnet through said contacts successively, and a group of switches for opening and closing the circuit through the respective contacts independently of said wiper; and a keyboard having 45 a bank of manually operable keys for each group of switches, said keys being each associated with one of the switches whereby the keys of each bank may be manually set to open the switches so as to cause each brush to control the magnet in accordance with a predetermined digit of a serial 50 number.

ERNEST ROSE.
